GUIDE MECHANISM

Thomas L. Burrell, Cleveland, Ohio

Application May 3, 1941, Serial No. 391,683

8 Claims. (Cl. 242—76)

This invention is an improvement in guides for directing continuously-moving strip material into a plurality of coiling devices.

Heretofore, many difficulties have arisen through the use of conventional guides or deflecting gates as applied to hot strip coilers in that the strip is soft and, as the end of the slab from which the strip is formed is not perfectly square, the leading end is usually in the form of a fishtail, so that by virtue of the bounding action of the strip passing along the conveyor the leading end is caused to strike the guide or deflector and become doubled back on itself. When it becomes necessary to remove such from the strip, as these difficulties arise, considerable loss of time and labor as well as loss due to shutdown of the mill is caused.

It is an object of this invention to provide apparatus for overcoming the objections to and the difficulties encountered in connection with the use of conventional hot strip coiler guides.

Another object of the invention is to provide a flexible strip guide which may be adjusted to suit various conditions encountered in the coiling of hot strip material as it issues from a mill.

A further object is to provide apparatus for positively forcing the leading end of the strip material down toward the conveyor in order to provide for freely feeding the strip to a coiler.

Still a further object of the invention is to provide a continuous belt, above the conveyor and inclined thereto, moving at a speed greater than that of the strip, for engaging the end of the strip and forcing it down against the conveyor to prevent its becoming fouled by striking the open gate leading to the coiler.

These and various other objects of the invention as well as its various other novel features and advantages will be apparent when the following detailed description is read in conjunction with the accompanying drawings of which:

Figure 1 is a plan view of the flying guide,

Figure 2 is a front elevation view, showing the guide in its high and low positions, taken at II—II of Figure 1,

Figure 3 is a side elevation view of the guide,

Figure 4 is a sectional view taken at IV—IV of Figure 2,

Figure 5 is a side elevation view of the flying guide in combination with a hot rolling mill, conveyor, guides and coilers, and

Figure 6 is a modification of the flying guide.

With reference to the drawings, the apparatus consists of a conveyor 1, strip guide unit 2,

deflecting gates 3 and 4, and conventional hot coilers 5 and 6.

The supporting structure of guide 2 consists of two plates 7 and 8 each of which is secured to the upper ends of long stud bolts 9, and two laterally extending I-beams 11 welded at their ends to the plates 7 and 8. Secured to one end of each of the two plates is an inclined member 12, the lower ends of which are rigidly secured to the side guards 13 of conveyor 1 to which are also secured the lower ends of stud bolts 9.

Slidably mounted on stud bolts 9 by means of guides 14, through which the bolts pass, are two vertically-movable tapering frames 15. At the lowermost portion of frames 15 are secured two bearing casings 16 within which the ends of shaft 17 are rotatably supported and at the front or upper portion of frames 15 are secured bearing casings 18 within which the ends of shaft 19 are rotatably supported. Around the two shafts 17 and 19 passes a heat-resistant continuous belt 21.

Above the I-beams 11 and supported thereby are two cylinders 22 retained in position by means of stud bolts 23 passing through plates 24 and threadably-engaging pads 25. Piston rods 26 extending from the bottom of cylinders 22 are pinned to lugs 27 welded to the frames 15. For raising and lowering frames 15 and the apparatus supported thereby, fluid pressure is applied to cylinders 22 through connecting pipes 28 from a suitable source of supply (not shown).

A cooling system for applying a spray of cooling fluid to the belt 21 and shafts 17 and 19 comprises a pipe 29 through which the coolant passes from a suitable source of supply (not shown) to two pipes 31 extending in opposite directions to laterally-positioned spray pipes 32. At the front or upper spray a curved baffle 33 is secured for directing the coolant downwardly toward the conveyor 1 so as to prevent its being thrown outwardly away from the apparatus. An adjusting valve 34 may be regulated for increasing or decreasing the flow of coolant to the two spray pipes.

Two motors 35 and 36 suitably supported on overhanging members 37 and 38 secured to one of the frames 15 are coupled to shafts 17 and 19 through couplings 17a and 19a respectively, and connected together electrically so that the same speeds may be maintained in order to prevent slippage between the belt and the shafts. Although not shown, suitable controls may be provided for driving the two motors 35 and 36 at any desired speeds.

Positioned across the conveyor 1 and adjacent to shaft 17 is an extended guide 39, secured at its front end to a spring 39a, against which strike the front or strip-deflecting ends of gates 3 and 4 when either one is raised for directing the strip to its respective coiling device. It will be apparent that when gate 3 is opened, the strip will pass downwardly between pinch rolls 41 and through throat 42 to coiler 5 and when gate 4 is opened, the strip will pass downwardly between pinch rolls 43 and through throat 44 to coiler 6.

A modified form of my strip guide unit disclosed in Figure 6 includes a supporting structure, adjusting mechanism, and cooling device similar to that provided for in the embodiment described heretofore. The continuous belt and the shafts over which it passes are replaced with a plurality of grooved rollers 51 and train of gears 52 driven from a suitable drive connected thereto. As will be noted, the raised portions of one roller are inserted in the grooves of the adjacent one so that the peripheries of the rolls overlap. A grill 53, properly secured to the side frames and covering the recess between adjacent rollers, is provided in order to prevent the leading end of the strip as it engages the guides from catching in the recess and doubling back on itself.

The apparatus having been described in detail the method of operating the flying strip guide may be briefly summarized as follows:

As disclosed in Figure 3, the vertically-movable frames 15 together with belt 21 and shafts 17 and 19 are lowered to the bottom position by applying fluid pressure to the upper end of double-acting pistons within cylinders 22, the motors 35 and 36 started, and valve 34 opened to permit the coolant to pass through the spray pipes 32 to the belt 21 and shafts 17 and 19. Depending upon the coiler into which the leading end of the strip is to pass, one or the other of gates 3 or 4 is raised to the open position.

At this juncture the strip is started through the mills. As it approaches the flying guide, there is a tendency for the leading end to extend upwardly away from the conveyor, which condition must be corrected by forcing the end downwardly against the conveyor in order that the strip be properly fed to the coilers. The belt 21, due to its inclined position, will engage the end of the strip intermediate the two shafts 17 and 19 and as it is traveling at a greater linear speed than that of the strip, will force the end down against the rolls of conveyor 1 and thus cause the strip to pass without difficulty to one of the coilers. As soon as the strip end has passed into one of the coilers, the frames 15 together with belt 21 and shafts 17 and 19 are raised to the upper position, as disclosed in Figure 4, by applying fluid pressure to the lower end of the double-acting pistons within cylinders 22, and retained in this position until another strip to be coiled issues from the mill or other strip-processing apparatus.

According to the provisions of the patent statutes, I have explained the principle and construction of my invention and have illustrated and described what I now consider to represent its best embodiments. However, I desire to have it understood that, within the scope of the appended claims, the invention may be practiced otherwise than as specifically illustrated and described.

I claim:

1. Apparatus for guiding strip material passing along a conveyor or the like comprising a pair of vertically-movable parallel frames, strip end-engaging means inclined to the horizontal mounted between said frames, means for actuating said strip end-engaging means, and means for adjusting said frames vertically.

10 2. Apparatus for guiding strip material passing along a conveyor or the like comprising a pair of vertically-movable parallel frames, strip end-engaging means inclined to the horizontal mounted between said frames, means positioned adjacent to said strip end-engaging means for applying a coolant thereto, means for actuating said strip end-engaging means, and means for adjusting said frames vertically.

15 3. Apparatus for guiding strip material passing along a conveyor or the like comprising a pair of movable parallel frames, strip end-engaging means inclined to the horizontal mounted between said frames, means positioned adjacent to said strip end-engaging means for applying a coolant thereto, means for actuating said strip end-engaging means, means for raising and lowering said frames, and guide means for restraining said frames to move substantially in a vertical direction.

20 4. Apparatus for use in combination with a conveyor and a plurality of coiling devices for guiding strip material comprising a pair of movable parallel frames, means inclined to the horizontal mounted between said frames for engaging said strip, means positioned adjacent to said strip-engaging means for applying a coolant thereto, means for actuating said strip-engaging means, guide means adjacent to said strip-engaging means restraining the strip to pass in a well-defined path beyond said last-mentioned means, means for raising and lowering said frames, and guide means for restraining said frames to move substantially in a vertical direction.

25 5. Apparatus for use in combination with a conveyor and a plurality of coiling devices comprising a pair of movable parallel frames, strip-guiding means inclined to the horizontal comprising a continuous belt passing over a pair of parallel shafts, means positioned adjacent to said strip-guiding means for applying a coolant thereto, means for actuating said strip-guiding means, a second guide means adjacent to said strip-guiding means for restraining the strip to pass in a well-defined path beyond said last-mentioned means, means for raising and lowering said frames, and guide means for restraining said frames to move substantially in a vertical direction.

30 6. Apparatus for use in combination with a conveyor and a plurality of coiling devices comprising a pair of movable parallel frames, strip-guiding means inclined to the horizontal comprising a continuous belt passing over a pair of parallel shafts, means comprising a plurality of spray pipes adjacent to and extending across said continuous belt for applying a coolant thereto, means for actuating said strip-guiding means, a yieldable guide means forming a restricted passage with the conveyor for restraining the strip to pass in a well-defined path beyond said last-mentioned means, means for raising and lowering said frames, and guide means for restraining said frames to move substantially in a vertical direction.

35 7. Apparatus for use in combination with a

conveyor and a plurality of coiling devices comprising a pair of movable parallel frames, strip-guiding means inclined to the horizontal comprising a plurality of rollers provided with a plurality of axially-spaced peripheral grooves and positioned so that the raised portions of one roller registers with the grooves of the roller adjacent thereto, means for actuating said strip-guiding means, means adjacent to said strip-guiding means for restraining the strip to pass in a well-defined path beyond said last-mentioned means, means for raising and lowering said frames, and guide means for restraining said

frames to move substantially in a vertical direction.

8. Apparatus for guiding strip material passing along a conveyor or the like comprising a pair of vertically-movable parallel frames, strip-engaging means mounted between said frames and inclined to the horizontal, means for actuating said strip-engaging means, means positioned adjacent to said last-mentioned means for applying a coolant thereto, coiling means for receiving strip material issuing from said strip-engaging means, and means for adjusting said frames vertically.

THOMAS L. BURRELL.
